(57) **CLAIM**

The ornamental design for a wall-mounted multifunctional electrical receptacle, as shown and described.

DESCRIPTION

FIG. 1 is a perspective view of a first embodiment of the wall mounted multifunctional electrical receptacle; showing our new design;

FIG. 2 is a front view thereof; FIG. 3 is a right side view thereof, the left side being a mirror image thereof;

FIG. 4 is a top plan view thereof, the bottom plan view being a mirror image thereof;

FIG. 5 is a rear view thereof;

FIG. 6 is a perspective view of a second embodiment of the wall mounted multifunctional electrical receptacle; showing our new design;

FIG. 7 is a front view thereof;

FIG. 8 is a right side view thereof, the left side being a mirror image thereof;

FIG. 9 is a top plan view thereof, the bottom plan view being a mirror image thereof;

FIG. 10 is a rear view thereof;

FIG. 11 is a perspective view of a third embodiment of the wall mounted multifunctional electrical receptacle; showing our new design;

FIG. 12 is a front view thereof;

FIG. 13 is a right side view thereof, the left side being a mirror image thereof;

FIG. 14 is a top plan view thereof, the bottom plan view being a mirror image thereof;

FIG. 15 is a rear view thereof;

FIG. 16 is a perspective view of a fourth embodiment of the wall mounted multifunctional electrical receptacle; showing our new design;

FIG. 17 is a front view thereof;

FIG. 18 is a right side view thereof, the left side being a mirror image;

FIG. 19 is a top plan view thereof, the bottom plan view being a mirror image thereof;

FIG. 20 is a rear view thereof;

FIG. 21 is a perspective view of a fifth embodiment of the wall mounted multifunctional electrical receptacle; showing our new design;

FIG. 22 is a front view thereof;

FIG. 23 is a right side view thereof, the left side being a mirror image thereof;

FIG. 24 is a top plan view thereof, the bottom plan view being a mirror image thereof; and,

FIG. 25 is a rear view thereof.

The design consists of the features of shape, ornament, pattern and configuration of the portion of the wall-mounted
